UNITED STATES PATENT OFFICE.

CLAUS DUECKER, OF NEW HOLSTEIN, WISCONSIN.

CHURN.

SPECIFICATION forming part of Letters Patent No. 391,520, dated October 23, 1888.

Application filed April 21, 1888. Serial No. 271,373. (No model.)

To all whom it may concern:

Be it known that I, CLAUS DUECKER, of New Holstein, in the county of Calumet and State of Wisconsin, have invented a new and 5 Improved Churn, of which the following is a full, clear, and exact description.

Reference is to be had to the accompanying drawings, forming a part of this specification, in which similar letters of reference indicate 10 corresponding parts in all the figures.

Figure 1 is a sectional elevation of a barrel-churn having my new dasher placed therein. Fig. 2 is an opposite section of the same, showing the diagonal arrangement of this dasher. 15 Fig. 3 is an edge view of the dasher, showing the hinged section; and Fig. 4 is a plan view of the dasher.

The invention will first be described in connection with the drawings, and then pointed 20 out in the claim.

A represents the body of the churn arranged to be revolved on trunnions *a a*, journaled in standards *B' B'*; and B represents my new dasher placed diagonally in and across 25 the churn, as shown clearly in Fig. 2. The dasher is composed of the main section C, upper short section, D, attached to the section C by hinge *b*, and the cross pins or rods E E, fitted in the said sections, as shown clearly in 30 the drawings.

The hinged section D is to enable the dasher to be placed in and removed from the cover-

opening F at one end of the churn, and to enable it to be fastened under the permanent flange G.

In use the hook *f* is detached from the eye *f'* and the section D tipped to one side. The dasher is placed in the churn with the bottom plate, *h*, to one side. The dasher is then tipped against the opposite side of the churn and the 40 section D turned in a straight line with the section B, so its plate *h'* comes beneath the flange G. The hook *f* is then engaged with the eye *f'*, so that in this manner the dasher is held firmly in place.

By placing the dasher in diagonal position the agitation of the cream is very effective, causing it to be churned to butter in a comparatively short time.

Having thus described my invention, what 50 I claim as new, and desire to secure by Letters Patent, is—

The churn herein shown and described, composed of the rotary body A, hung upon trunnions, and the dasher C, placed diagonally 55 across the body and formed of the section C, rods E, and section D, hinged to the upper end of the section C and adapted to be locked in line therewith, substantially as described.

CLAUS DUECKER.
